UNITED STATES PATENT OFFICE

2,515,817

EXPANSION BRACELET

Karl C. Augenstein, Cranston, R. I., assignor to
 Speidel Corporation, Providence, R. I., a corporation of Rhode Island

Application April 9, 1947, Serial No. 740,396

2 Claims. (Cl. 59—79)

1

This invention relates to expansion bracelets and the like articles embodying self-retracting linkages.

Bracelets of the above type comprise pivotally interconnected links associated with retracting springs, each of the links carrying an ornamental shell which provides an attractive exterior. In such constructions there is a tendency for the retracting springs to cause the bracelet to assume a twisted form when the links are retracted, such a tendency varying according to the shape or design of the individual links or shells of the bracelet. It has, therefore, been the usual practice to use outer shells having a shape which minimize this tendency to twist the bracelet, such, for example, as an elongate S-shape, a dumb-bell shape, etc., although it is highly desirable to use other shapes or designs if it were otherwise feasible.

Another difficulty involved in the manufacture of such bracelets is that in applying the ornamental shells sufficient space should be maintained between the top of the shell and the associated link to accommodate the end of the retracting spring, and since the shells are applied over the links there is a danger of telescoping or forcing the shells too far inwardly with consequent injury to the spring.

The principal objects of the invention are to provide a construction which reduces, if not entirely eliminates, the tendency to twist the bracelet so that the links may be formed in an unlimited number of shapes or designs; and to provide a construction which prevents the shells from being forced too far inwardly, thereby overcoming the danger of injuring the retracting springs.

Further objects relate to various features of construction and will be apparent from a consideration of the following description and the accompanying drawings, wherein:

Fig. 1 is a top plan view of a bracelet embodying the present invention;

Fig. 2 is an enlarged top plan view, with parts broken away, of a portion of the bracelet shown in Fig. 1;

Fig. 3 is an enlarged bottom view, with the shells removed from the bottom links, of the assembly shown in Fig. 2;

2

Fig. 4 is an enlarged edge or side view of the bracelet;

Fig. 5 is a section on the line 5—5 of Fig. 2;

Fig. 6 is an isometric view of a top link;

Figs. 7 and 8 are bottom and side views, respectively, of a shell for the top link shown in Fig. 6;

Fig. 9 is an isometric view showing the assembled shell and top link;

Fig. 10 is an isometric view of a bottom link;

Fig. 11 is an isometric view of a shell for the bottom link shown in Fig. 10;

Fig. 12 is an isometric view of the assembled shell and bottom link; and

Fig. 13 is an enlarged isometric view of the spring associated with each pair of top and bottom links.

In accordance with the present invention I provide a bracelet which comprises a plurality

20 of pairs of pivotally interconnected links, such, for example, as shown in Patent Nos. 2,225,746, granted December 24, 1940, and 2,267,967, granted December 30, 1941, each pair of links being

25 pivotally connected and associated with a spring or the like resilient member which normally holds the links in retracted position. Each pair

30 of links comprises an elongate top link and a bottom link and the longitudinal edges of at least one of the links, preferably the top link,

35 are formed with laterally projecting shoulder portions shaped to engage the adjacent shoulder portions of the corresponding links of the next pairs, the engaging shoulder portions of the several pairs being shaped to provide a surface con-

30 tact with each other preferably substantially co-extensive with the areas of their lateral edges.

The surface contact thus provided is effective to hold the several pairs of links in properly aligned relation when retracted by the springs. An ornamental shell fits over such links and each

40 shell is formed with recesses in its side walls through which the shoulder portions of the associated link project, thus preventing the shell from interfering with the action of the shoulder

45 portions.

With this construction and arrangement the retracted links are not only normally held in proper alignment and substantially free from any tendency to twist, but also the recessed walls

50 of the shells, being seated on the shoulder por-

tions of the associated links, prevent the shells from being forced or telescoped too far inwardly about the links and thus maintain sufficient spacing between the top of the shells and the links to accommodate and prevent injury to the ends of the retracting springs.

Referring to the accompanying drawings which show what is now considered a preferred embodiment illustrating the application of the invention to one of the above mentioned types of bracelets, the numeral 1 designates a bracelet comprising a plurality of pairs of interconnected links including a top link 2 and a bottom link 3. Since the bracelet here shown is of the equalizing link type, the links 2 and 3 are pivotally connected at their centers by hollow studs 5 which may be formed integral with the top links 2 and the opposite ends of each top link are pivotally interconnected with the opposite ends of the bottom links of the next pair of links by studs or pivots 6 which may likewise be formed integral with the top links 2, as shown in Figs. 6 and 9. The hollow studs 5 project through central openings 8 (Fig. 10) formed in the bottom links 3 and the pivots 6 project through openings 9 formed in the end portions of the links 3, the free ends of the studs 5 and pivots 6 being peened over, as indicated by numerals 5a and 6a of Fig. 3, to prevent the links from becoming disconnected. A coil spring 10 is received in each tubular stud 5 with one arm or free end 11 extending along the top link (Fig. 5) and its other arm 12 extending along the bottom link (Fig. 5) and being anchored in fixed position by an inwardly bent lug or tab 14 formed integral with the bottom link 3 (Fig. 10).

The longitudinal edges of the top links 2 are formed with laterally projecting shoulders 15 and 16 (Figs. 6 and 9), the shoulders 15 extending from a point *a*, spaced inwardly from one end of the link, to the point *b*, spaced inwardly from its opposite end, and the shoulder 16 likewise extending between points *c* and *d* on the opposite longitudinal edge of the link. Since the top links of the present embodiment are serrated or zig-zag shaped, the shoulder portions 15 and 16 are V-shaped and their edges provide flat surfaces engageable with those of the corresponding links of the next adjacent pairs, the engaging surfaces being substantially co-extensive and thus are effective to hold the links in proper alignment when in retracted position, as shown in Figs. 2 and 3.

An ornamental shell 20 (Figs. 7 and 8), designed to fit over the link 2, is formed with recesses 21 and 22 in its side walls to receive the shoulders 15 and 16, respectively, and adjacent to the ends of these recesses the shell is formed with bendable tabs 24. When the parts are assembled the tabs 24 are bent inwardly over the link 2 so as to hold the parts together and it will be noted that one of the side walls of the shell provides an abutment against which the end 11 of the retracting spring acts, as shown in Figs. 2 and 5. It will also be noted that the recessed portions 21 and 22 seat on the shoulders 15 and 16, as shown in Fig. 9, and thus not only accommodate the shoulders so that they may function as above described, but also prevent the shell from being pressed too far inwardly about the link, thus providing sufficient space between the top of the shell and upper face of the link, as shown in Fig. 5, to prevent injury to the spring 10.

The bottom links 3 are likewise formed with 75

lateral shoulders 25 and 26 which, if desired, may be designed to perform both of the above described functions of the shoulders of the top link. In this embodiment the bottom links are so designed that their longitudinal edges are not only spaced from one another, as shown in Fig. 3, and hence are not utilized to align the links, but only to provide a seat for the ornamental shells 30. These shells are formed with recessed side walls 31 and 32 shaped to receive the shoulders 25 and 26, respectively, as shown in Fig. 12, the parts being held in assembled relation by the inwardly bent tabs 34 which are integral with the shell 30. The recessed portions 31 and 32 seat squarely on the shoulders 25 and 26 and thus prevent the shells 30 from being pressed too far inwardly about the links 3, thereby insuring sufficient spacing between the shells and links to accommodate the ends 12 of the springs 10, as illustrated in Fig. 5.

It is apparent from the foregoing that an expansion bracelet of either of the above mentioned types embodying the present invention may be designed with links and shells of any desired shape or configuration, and that the shoulder portions of the links are effective not only to maintain the links in properly aligned relation, but also to insure adequate spacing between the shells and the links to prevent injury to the retracting springs.

While I have shown and described one desired embodiment of the invention, it is to be understood that this disclosure is for the purpose of illustration and that variations, changes and modifications may be made without departing from the spirit and scope of the invention as set forth in the appended claims.

I claim:

1. An expandable linkage comprising a series 40 of elongate upper links and a series of elongate lower links, the upper links being pivotally interconnected to the lower links, the longitudinal edges of the links of at least one of said series of links having laterally projecting parts, resilient means associated with said upper and lower links operative normally to maintain them in retracted position, a shell associated with each link, the shells associated with the links of the series having said laterally projecting parts having depending flanges formed with recessed portions, said recessed portions seating on said laterally projecting parts, thereby to prevent said shells from being forced too far toward said links having said laterally projecting parts, the non-recessed portions of said flanges fitting about the corresponding edge portions of said links of the series having said laterally projecting parts and being intermediate said laterally projecting parts, and an inwardly extending member on at least one of said non-recessed portions located on each longitudinal side of each shell associated with said links of the series having said laterally projecting parts, said inwardly extending members of each shell overlapping the link with which it is associated for holding the shell thereon.

2. An expandable linkage comprising a series of elongate upper links and a series of elongate lower links, the upper links being pivotally interconnected to the lower links, the longitudinal edges of the links having laterally projecting parts, resilient means associated with said upper and lower links operative normally to maintain them in retracted position, a shell associated with each link, the shells having depending flanges formed with recessed portions, said recessed por-

tions seating on said laterally projecting parts, thereby to prevent said shells from being forced too far toward the links, the non-recessed portions of said flanges fitting about the corresponding edge portions of the links intermediate said laterally projecting parts, and an inwardly extending member on at least one of said non-recessed portions located on each longitudinal side of each shell, said inwardly extending members of each shell overlapping the link with which it is associated for holding the shell thereon.
